(57) **CLAIM**

The ornamental design for a horizontal bar, as shown and described.

DESCRIPTION

FIG. 1 is a front, left and top perspective view of a horizontal bar showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a detail view of area 9 in FIG. 1.

The dash-dash broken lines show portions of the horizontal bar that form no part of the claimed design. The dash-dot broken lines in FIGS. 1 and 9 depict the bounds of the detail view and form no part of the claimed design.

1 Claim, 9 Drawing Sheets
